UNITED STATES PATENT OFFICE.

ENGELBERT MUELLER, OF RESERVE TOWNSHIP, ALLEGHENY COUNTY, PENNSYLVANIA.

ARTIFICIAL LEG.

1,315,323.

Specification of Letters Patent.

Patented Sept. 9, 1919.

Application filed August 2, 1918. Serial No. 248,028.

To all whom it may concern:

Be it known that I, ENGELBERT MUELLER, residing at Reserve township, in the county of Allegheny and State of Pennsylvania, 5 a citizen of the United States, have invented or discovered certain new and useful Improvements in Artificial Legs, of which improvements the following is a specification.

My invention relates to artificial legs 10 which include thigh and lower leg sections pivotally connected to each other to form a knee joint, and the object thereof is to provide an artificial leg wherein the lower leg sections may, when the wearer is walking, be brought to its forward position in alignment with the thigh section without the necessity of the wearer exerting, by his shoulder or otherwise, an intermittent pull upon the leg-supporting body member.

20 In the accompanying sheet of drawings, which forms part of my specification, I have illustrated the preferred embodiment of my invention. Figure 1 is a perspective view of the artificial leg; Fig. 2 a vertical central sectional view to enlarged scale of the knee joint; the plane of section being perpendicular to the pivotal axis of the thigh and lower leg sections; and Fig. 3 a sectional view taken on the line III—III, 25 Fig. 2.

Artificial legs of the character shown herein are for amputations above the knee joint. Their general construction is well known, the leg consisting of a thigh section 1 and a lower leg section 2 pivotally connected 35 at the knee joint to the thigh section, the two leg sections being provided with coöperating stops to limit particularly the forward movement of the lower leg section.

40 As such legs are usually constructed, a cord engages the lower leg section at a point in front of the pivotal axis of the leg sections, and is attached to a leg-supporting body member in such a manner that, when 45 a wearer in taking a step causes the lower leg to swing backwardly, he may, by exerting an upward pull upon the cord before placing the foot upon the ground, cause the lower leg to again swing forwardly into 50 alignment with the thigh section. Usually the pull upon the cord for thus bringing the lower leg section forwardly is exerted by the wearer raising his shoulder to a greater or less extent, and this must be 55 done for each step taken.

In the practice of my invention, the lower leg section is brought forwardly without alternately increasing and decreasing the effective length of the cord section. This I accomplish by providing the upper portion 60 of the lower leg section with two cord bearings, one arranged forwardly and the other rearwardly of the pivotal axis of the leg sections, the former bearing being disposed at a greater radial distance from the pivotal 65 axis than the latter. Extending around these bearings and preferably below the pivotal axis of the leg section, I provide a cord, and attach its opposite ends to the leg-supporting body member so that when the 70 leg is raised to take a step forwardly, the weight of the leg sustained by the cord and acting through the forward bearing causes the leg section to move into alignment with the thigh section. In the movements of the 75 lower leg section the cord is not, by reason of the presence of the rearward cord bearing, elongated to any substantial extent.

Referring to the illustrative embodiment of my invention, the upper portion of the 80 lower leg section 2 may have a hinge-forming member 3 attached to it, as by means of a pin 4. Through the upper portion of the member 3 and the lower ends 5 of the thigh section 1, a suitable horizontal pivot 6 connects the two leg section to each other for the proper swinging movement of the lower leg section. The pivot or joint 6 may, as indicated, consist of a bushing suitably held in place as by means of a screw 8. The cord 90 bearings are preferably in the form of rollers 9 and 10, the forward roller 9 being disposed at a considerably greater radial distance from the axis of the pivot 6 than the rear roller 10. The cord 11 is connected 95 at both ends to a leg-supporting body member, and extends around the cord bearings or rollers 9 and 10 and below the axis of the pivot 6. Preferably such member comprises a belt 12 and shoulder-strap 13. One 100 end of the cord 11 is attached to the front of the belt 12, and from such connection the cord extends downwardly in front of the thigh section, upwardly at the rear thereof, and has its upper end attached to the rear 105 of such belt.

While the main portion of the weight of the leg is carried by the cord 11, a side strap 14 may connect the thigh section 1 to the belt 12 to carry a portion of the weight, or 110

such strap may be provided merely for the purpose of supporting the leg in case the cord 11 breaks.

As is usual in legs of the sort contemplated herein, the thigh and lower leg sections are provided with coöperating stops to limit the forward movement of the lower leg sections. As shown herein the lower portion of the thigh section is provided with 10 a stop 15 adapted to coöperate with a stop 16 formed on the upper end of the member 3.

In walking, a wearer, in the usual manner, causes the lower leg section to swing rearwardly during the initial movement of 15 taking a step. As the thigh section is moved forwardly, the weight of the leg, acting with greater leverage through the forward cord bearing 9 than through the rearward bearing 10, causes the lower leg section to gradually, 20 and not jerkily, move into alinement with the thigh section. This straightening of the leg is accomplished, as already explained, without the wearer exerting a pull upon the cord 11, as by raising his shoulder, or 25 otherwise.

According to the provisions of the patent statutes, I have described the principle and

operation of my invention together with the leg construction which I now consider to represent the best embodiment thereof. 30 However, I desire to have it understood that, within the scope of the appended claim, my invention may be practised with other forms of construction than that particularly shown herein.

I claim as my invention:

In an artificial leg, the combination of a leg-supporting body member, thigh and lower leg sections pivotally connected to each other, said lower leg section being provided with two cord bearings arranged one forwardly and the other rearwardly of the pivot axis of the leg sections, the forward bearing being at a greater radial distance from said axis than the rearward bearing, and a cord extending around said bearings and having its opposite ends attached to said body member.

In testimony whereof I have hereunto set my hand.

ENGELBERT MUELLER.
